UNITED STATES PATENT OFFICE.

BURT WARREN TOUCHSTONE, OF ELDORADO, ARKANSAS.

FENCE POST.

Application filed October 26, 1926. Serial No. 144,370.

This invention relates to fence posts and the general object of the invention is to provide a fence post which may be very cheaply made, which is very strong and rigid, and which is so constructed as to hold and clinch the staples used in supporting fence wire on the post.

A further object is to provide a fence post formed of sheet metal which is folded upon itself, the folded portion then being bent to thus provide a curved staple receiving space, the side walls of this space being formed with staple receiving channels which extend out to the front face of the post to act as seats for the fence wire, the staple receiving channels receiving the two legs of the staple and the staple receiving space acting to clinch the staple when driven home.

My invention is illustrated in the accompanying drawings wherein:

Figure 1 is a perspective view of a fence post constructed in accordance with my invention;

Fig. 2 is a transverse sectional view thereof;

Fig. 3 is a face view of the sheet from which the fence post is made;

Fig. 4 is a section on the line 4-4 of Figure 2;

Fig. 5 is a top plan view of the sheet shown in Figure 3.

Referring to these drawings and particularly to Figure 5 it will be seen that the fence post is formed of a sheet of metal which is bent upon itself so as to provide two side walls 10. The inner faces of these side walls are formed with transversely extending grooves or channels 11, these being formed before the sheet metal is bent. After the sheet metal has been bent into an approximate V-shaped form, as illustrated in Figure 5, the folded sheet is bent around in a curve, as at 12, see Figure 2, while the lateral margins of the folded sheet are bent outward and then inward so as to form wings 13. The space 14 defined by the walls 10 constitutes a staple receiving space and the grooves 11 constitute seats for the legs of the staples. These grooves extend out upon the rounded portions 15 constituting the face of the fence and thus provide wire receiving seats.

In use the wire A is disposed in the cor-

responding wire receiving space and then the staple is driven home with its legs disposed in the grooves 11. As the staple is driven home, the ends of the legs will be curved around within the space 14, as illustrated in Figure 2, and thus the staple will be clinched and the wire A drawn inward into the space between the two wing portions of the fence post. Thus, the wires will be held from any vertical movement within the wire spaces, the staple will be held from pulling out by being clinched, and from any vertical movement because the legs are disposed within the seats 11. The fence post itself will be particularly strong because of its corrugated form. I do not wish to be limited to the exact form of the post as this might be varied in some respects without departing from the spirit of the invention. Preferably the post will be set in a concrete base but obviously I do not wish to be limited to this.

I claim:

1. As an article of manufacture, a fence post formed of sheet metal, folded upon itself to provide rearwardly and transversely curved webs and two laterally and rearwardly projecting wings extending from the webs, the side walls of the folded webs being spaced from each other to receive a staple between them and being provided with staple leg receiving grooves.

2. As an article of manufacture, a fence post formed of sheet metal, folded upon itself to provide a rearwardly and transversely curved body portion and two laterally and rearwardly projecting wings, the side walls of the folded body portion being spaced from each other to receive a staple between them and being provided with staple leg receiving grooves, said grooves extending out upon the face of the post on each wing thereof to provide a seat for the fence wire.

3. As an article of manufacture, a fence post formed of sheet metal folded upon itself to provide two adjacent webs rearwardly and laterally curved in the same direction and approximately concentric to the same center, and two laterally and rearwardly projecting wings extending from the webs and disposed in divergent relation.

In testimony whereof I hereunto affix my signature.

BURT WARREN TOUCHSTONE.
